CLAIM

I claim the ornamental design for a display with digital video disc player for automobile, as shown and described.

DESCRIPTION

FIG. 1 is a top perspective view of a display with digital video disc player for automobile of the present invention; FIG. 2 is a front view thereof;

FIG. 3 is a top view thereof;

FIG. 4 is a rear view thereof;

FIG. 5 is a bottom view thereof;

FIG. 6 is a first side view thereof; and,

FIG. 7 is a second side view thereof.

The ornamental design which is claimed is shown in solid lines in the drawings. Any broken lines in the drawings are for illustrative purposes only and form no part of the claimed design.
